RADIO CONTROL CIRCUIT

Laurence M. Perkins, Erie, Pa., assignor, by mesne assignments, to Radio Corporation of America, New York, N. Y., a corporation of Delaware

Application October 14, 1932, Serial No. 637,681

10 Claims. (Cl. 250—20)

This invention relates to a control circuit for a radio receiver and more particularly to an automatic output control and auxiliary manual controls to supplement the action of the automatic control.

In the ordinary automatic output circuits, where an auxiliary control tube is used, the control tube is connected across the detector tuned circuit in such a way that it adds capacity to that circuit, and prevents it from tracking with the other tuned circuits across the band of frequencies to be received. Such circuits, also, do not have a control for limiting the maximum sensitivity which the automatic control will cause the receiver to have when passing between stations in tuning, or when receiving a very weak station. Hence, the noise at those times may be very great. Another feature which those circuits do not have, is that of automatically controlling the detector tube at the same time an intermediate or radio frequency amplifier tube is controlled.

An object of this invention is to provide a new improved automatic gain control for a radio receiver.

Another object of this invention is to provide an automatic output control having a manual control for the maximum sensitivity which the automatic control can cause the receiver to reach. This feature provides a means for limiting the amount of noise picked up between stations as the receiver is tuned, as well as the noise received along with weak stations. This has been accomplished by providing a potential control for one of the elements of the control tube.

Another object of this invention is to provide an automatic output control having a manual control for the audio frequency stages to control the audio frequency output for a given detector output. This has been accomplished by providing the by-pass or voltage divider circuit between the detector output and audio frequency amplifier.

Another object of this invention is to provide an automatic volume control having a manual control for adjusting the volume level at which stations are to be received. This has been accomplished by providing a manual detector grid bias control and a manual grid bias control for the radio or intermediate frequency amplifier.

Another object of this invention is to make use of a desirable characteristic of the automatic volume control tube for accomplishing the control. This feature has the advantage of permitting very good control with a low potential on the plate of the control tube. This has been accom-

plished by supplying the proper potentials to the elements of the automatic volume control tube to cause it to operate on the desirable portion of its characteristic.

Another object of this invention is to control the detector tube as well as the radio or intermediate frequency amplifier tubes from the automatic volume control system. Since the detector has different operating characteristics than the amplifier this has been accomplished by controlling the detector and amplifier from different portions of the automatic control circuit.

Another object of this invention is to provide a connection for the actuation of the automatic control tube which does not unbalance the detector stage, or prevent it from properly tracking with the other stages of the receiver. This has been accomplished by connecting the control element of the automatic control tube to the detector in such a way that the capacity in the control circuit is not connected across the detector tuned circuit.

Further objects and advantages of the present invention will be apparent from the following description, reference being had to the accompanying drawing wherein a preferred embodiment of one form of the present invention is clearly shown.

In the drawing:

Fig. 1 discloses a schematic diagram of a preferred form of the present invention. In this modification a radio frequency amplifier stage has been indicated as accompanying the control circuit, but it is understood that an intermediate frequency stage might be used or controlled instead of a radio frequency amplifier and still come within the scope of the invention.

Fig. 2 discloses a schematic diagram of a modification, showing the control potential taken from a different point of the control circuit than that shown in Fig. 1.

With particular reference to Fig. 1 of the drawing, 1 represents a radio frequency amplifier having a thermionic tube 10 which has a plate 12, a control grid 14, a cathode 16, an auxiliary grid 18, and the heater 20. As would be apparent to one skilled in the art, the input from a preceding stage would be connected to the grid 14 and cathode 16. The cathode 16 is grounded at 22. The auxiliary grid 18 is connected to a source of potential through a lead 26. The heater 20 is connected through its terminals 28 and 30 to a suitable source of potential. The plate 12 is connected to one end of a choke 24, which at its other end, 55

connects to a plate potential source through the lead 32. Condensers 34 and 36 are by-pass condensers and by-pass high frequency currents from the plate 12 and auxiliary grid 18, respectively, 5 to ground at 22. Condenser 38 is a coupling condenser and furnishes capacity coupling between the circuit of the plate 12 and an inductance 40, through connections to the plate 12 and to one side of the inductance 40. Inductance 40 forms 10 part of a tunable resonant circuit 46, composed of the inductance 40, a condenser 42 in series with the inductance 40, and a variable condenser 44 connected across the inductance 40 and condenser 42. One side of the condenser 42 is connected to 15 the inductance 40 and the other side to a ground at 48, thus isolating the inductance 40 and preventing a D. C. potential from the ground 48 from being transferred through the inductance 40 to the input of a succeeding tube through a lead 20 50. The biasing potential for the succeeding tube is applied to the grid of that tube thru the lead 50, inductance 40 and a suitable lead 41. A condenser 52 grounded on one side at 48 serves as an isolating and by-pass condenser to prevent 25 D. C. potentials from the ground 48 from being applied to the input of a succeeding stage through a lead 54 connected to its other side.

A detector 100 has a plate 102, a control grid 104, an auxiliary grid 106, a cathode 108, and a 30 heater 110 therein. The heater 110 is connected to a suitable source of potential through its terminals 112 and 114. The input circuit connected between the grid 104 and cathode 108 includes a tunable resonant circuit 116 having an inductance 35 118 connected at one end to the grid 104 and at its other end to an isolating condenser 122. A variable condenser 120 is connected across the series combination of the inductance 118 and the condenser 122 to tune the circuit to resonance at 40 a desired frequency. The isolating condenser 122 is used in this stage to make it similar to the preceding stage so it will track therewith. Then, too, in a tuned radio frequency receiver, the rotor plates of the condenser 120 would ordinarily be 45 grounded. However, in a superheterodyne receiver, the condenser 122 might not be used since in that case one side of the condenser 120 would not ordinarily be grounded. A condenser 124 connected at one end to condenser 122 and at the 50 other to the cathode 108 is also an isolating condenser, and while it also makes this stage similar to a preceding stage or stages, the two condensers 122 and 124 isolate the grid circuit from a cathode circuit so that a D. C. potential may be applied 55 therebetween. The cathode 108 is connected to the negative side of the power supply at a terminal 126 on a secondary 128 of a power transformer through a filter choke 130 and resistors 132 and 134. Resistor 132 has a movable contact 136 connected to one of its ends and capable 60 of short circuiting any desired portion of the resistor. A resistor 138 is connected at one end to the inductance 118, between that inductance and the condenser 122. The other end of resistor 138 connects to a terminal of resistor 132 65 between that resistor and the choke 130. The cathode 108 is connected to ground at 142 through a choke 146 and a blocking condenser 182 and to a control electrode 144 of a control tube 140 through the choke 146. The condensers 124 and 70 182 and the choke 146 form a radio frequency filter.

With particular reference to Fig. 2 of the drawing, the parts bearing the same numbers as those 75 of Fig. 1 perform the same function, and are sim-

ilar except perhaps for resistance values. However, in this modification, the lead 180 which supplies the control potential to the amplifier grids is connected to a point 400 on a resistor 166a intermediate the ends of that resistor. 5

In some cases, it may be desirable to have a greater difference of potential between the anode 148 and auxiliary grid 150 of the control tube 140 than is desirable for a biasing potential for the controlled tubes. In this case, the modification shown in Fig. 2 might be used. The point 400 on resistor 166a may be given a value such that the desired difference of potential may be obtained between that point and the anode 148. Thus, the potentials of the cathode 108, and the 15 control electrode 144 are determined by the potential drop across the resistors 132 and 134, and may be manually varied by varying the position of the contact 136 on resistor 132. The value of resistor 134 determines the minimum potential. 20 Resistor 138 allows the negative potential from terminal 126 through the choke 130 to be applied to the grid 104 and serves as an impedance to the flow of alternating current from the resonant circuit 116. The choke 146 tends to prevent the 25 alternating currents of the circuit of cathode 108 from being applied to the control electrode 144 of the control tube 140, but allows the D. C. potential of the cathode 108 to be applied to the 30 control electrode 144. The control tube 140 has, beside the control electrode 144, a plate 148, an auxiliary grid 150, a cathode 152, and a heater 154 therein. The heater 154 is connected to a suitable source of potential through its terminals 156 and 158 to heat the cathode 152. The auxiliary grid 150 is connected to ground at 160. The cathode 152 is grounded at 154 through a blocking condenser 162. The condenser 162 prevents the D. C. ground potential from being applied to the cathode 152. The plate 148 of the control 35 tube 140 is connected, through a resistor 166 and a variable tap 168 on a resistor 172 to a voltage divider formed by resistors 170, 172, 174 and 176. Resistors 170, 172, 174 and 176 are connected in 40 series, with a terminal of resistor 170 forming one extremity of the series connection, and grounded at 178, and a terminal of resistor 176 forming the other extremity and connected to one terminal of the choke 130 between that choke and the resistor 132. The potential of the cathode 152 of the tube 140 is provided by the connection of that cathode to a point intermediate the resistors 174 and 176. The potential of the plate 148 of the tube 140 is supplied through the variable tap 168 on the resistor 172. The value of the resistor 172 with respect to the other resistors 170, 174 and 176 governs the limits of the potential variations 45 on the plate 148. The plate 148 of the tube 140 is also connected to the grid 14 of tube 10 or 50 grids of the amplifier tubes which are to be controlled. As many amplifier tubes as may be desired may be controlled to obtain the desired result. This connection is made through the lead 180. A bypass condenser 182 is connected 55 between the plate 148 and ground at 178 to bypass high frequency currents from the plate circuit to ground. Hence, it may now be seen that any variations in the potential of the cathode 108 of the detector tube 100 will cause similar 60 variations in the potential of the control electrode 144 of the tube 140, and consequently variations in the current flow between the plate 148 and cathode 152 of the tube 140. 65

The power supply utilizes the conventional 70 75

type of rectifier 200 having plates 202 and an electron emitting element or filament 204 therein. The plates 202 are connected to the extremities of the transformer secondary 128. The filament 204 is connected across an auxiliary secondary coil 206 of the same transformer, or a separate transformer secondary providing the proper voltage. The positive lead from the rectifier which is connected to one side of the filament 204, is connected to one extremity of a voltage divider, composed of resistors 210, 212, 214 and 216 and high resistance choke 224, through a choke 208. A condenser 218 is connected across the choke 208 to form a part of the filter circuit. Condensers 220 and 222 are connected in series across the choke and their mid tap is connected to a lead from the terminal 126 of the coil 128. These condensers form a by-pass for the ripple voltage. The lead from the tap 126, which is the negative lead, is connected to the other extremity of the voltage divider formed by the resistors 210, 212, 214 and 216, and the speaker field 224 which forms an additional choke and a part of the voltage divider. The point intermediate the resistor 216 and the speaker field 224 is grounded at 226. A condenser 228 also connects to a point intermediate the resistor 216 and the speaker field 224 and to a point intermediate the resistor 210 and the choke 208, and forms an additional ripple by-pass circuit in the filter system. A condenser 230 is connected between the end of the choke 130 intermediate that choke and the resistor 132, and the ground at 226. The potential of the auxiliary grid 106 of the detector 100 is supplied from a point intermediate the resistors 214 and 216. The potential for the amplifier auxiliary grid and plate is supplied from a point intermediate the resistors 212 and 214 and a point intermediate the resistors 210 and 212 through leads 232 and 234, respectively. The potential of the plate 102 of the detector 100 is supplied from an extremity of the voltage divider intermediate the resistor 210 and the choke 208 through an impedance 236 having a variable tap 238, the choke 240 and the choke 242. The condensers 244 and 246 connected to the plate and the auxiliary grid, respectively, of the detector 100 and to the cathode through a common connection form by-pass circuits for high frequency currents. The condensers 248 and 250 connected in series and across the choke 240 and grounded at their mid tap at 252 together with the chokes 240 and 242, form an output filter for the detector circuit. The choke 242 is preferably a radio frequency choke, and the choke 240 is preferably a high frequency audio frequency choke. The choke 240, however, may be omitted when desirable.

The tube 300 having anode 304, a grid 306 and a filament 308, and the tube 302 having an anode 314, a grid 312 and a filament 310 are connected in a push-pull audio frequency amplifier circuit. The grid 306 and a terminal of an input impedance 316 are connected through an isolating condenser 235 to the detector output filter at a point intermediate the choke 240 and the impedance 236. The grid 312 of the tube 302 is connected to the other extremity of the input impedance 316. The filaments 308 and 310 of the tubes 300 and 302 respectively are connected in parallel and supplied by a suitable heating potential through the leads 318 and 320. The anodes 304 and 314 of the tubes 300 and 302 respectively are connected each to an extremity of

a primary 324 of an output transformer 322. The terminals of the secondary 326 of the output transformer 322 are connected across the terminals of the voice coil 328 of a loud speaker 330. The D. C. potential of the grids 306 and 312 is supplied from a point intermediate the resistors 174 and 176 through a resistor 334 and a tap 332 on the input impedance 316. A condenser 336 connected from a point intermediate the resistor 334 and the tap 332 to ground at 178 forms a by-pass circuit. The D. C. potential on the anodes 304 and 314 of the tubes 300 and 302 is supplied from a point intermediate the resistor 210 and the choke 208 through a tap 338 on the primary 324 of the output transformer 322.

The impedance 236 has a movable contact 238 connected to one of its extremities and forming a variable contact intermediate its extremities so that a desired portion of the impedance may be short circuited. Variations in this impedance vary the impedance of the path of the plate current of the detector 100 and the impedance of an audio frequency by-pass circuit.

Since one extremity of the voltage divider formed by the resistors 170, 172, 174 and 176 is connected to the negative terminal 126 through the choke 130 and at its other extremity to ground, and since the auxiliary grid 150 of the control tube 140 is connected directly to ground, while the plate 148 of the control 140 is connected through a resistor 168 to the point on the voltage divider intermediate the negative lead and ground it is apparent that the plate 148 is at a lower potential than the auxiliary grid 150. In fact, these potentials are so evaluated that the tube 140 acts on the desirable portion of its characteristic. Since the cathodes of the controlled amplifier tubes are at ground potential, and the grid of those tubes at the potential of the plate 148, it is also apparent that a negative bias is provided for those amplifier tubes. The fact that in this circuit the plate 148 may be operated at a lower potential than the auxiliary grid 150 shows clearly that the control tube can be any one of a number of varieties of tubes which operate with the auxiliary grid at a higher potential than the plate. This includes the pentodes and certain tetrodes which have their secondary emission limited.

Since the detector cathode 108 is connected to the negative lead through the resistors 134 and 132, that cathode will be above the potential of the negative lead by the potential equal to the drop of the resistors 134 and 132. Then, since the grid 104 of the detector is connected to the negative lead through the resistor 138 and the inductance 118, the potential of that grid will be more negative than that of the cathode because under normal operating conditions no current will flow through the resistor 138, and hence there will be no drop in the potential across that resistor.

Variations in the strength of the signals received will cause variations in the current flow from the anode 102 to the cathode 108 of the detector 100. Those variations of current flow will vary the potential drop across the resistors 134 and 132, and consequently the potential of the cathode 108. Since the control electrode 144 of the control tube 140 is connected to the cathode 108 of the detector through the choke 146, the potential of that control electrode will be varied with that of the cathode. The result of the variations in the potential of the control electrode 144 will be to vary the current flow between the

plate 148 and the cathode 152 of the control tube 140. This variation in current flow will vary the potential of the plate 148 due to the drop in the resistors 166, 172 and 170. The potential of the 5 grid of the controlled amplifier tube will vary simultaneously with that of the plate 148 due to their connection. In this manner, the gain or sensitivity of the amplifier tube is varied in response to variations in the strength of incoming signals.

Variations in the potential drop across resistors 134 and 132 due to variations in signal strength in the detector tube, while changing the potential of the cathode, do not appreciably change 15 the potential of the grid 104. The variations in the relative potential of the grid 104 and cathode 108 amount to variations in bias of the detector tube and vary its gain or sensitivity. Variations in the value of resistor 132, by moving the variable contact 136 and short circuiting part of that resistor, control the possible minimum bias for the detector 100 and the control tube 140, thus controlling the current flow through those tubes. Variations of the movable contact 136 also 20 controls the sensitivity of the high frequency amplifier thru its effect on the control tube action since it varies the voltage applied to the control tube. This control is particularly desirable for compensating for the different modulation percentages of different stations. That is, it changes the 25 action of the control tube so that the audio frequency output at the impedance 236 may be maintained practically constant for signals with either high or low percentages of modulation. It prevents overloading of the detector when signals having high percentage modulation are received and permits the detector to be used at high efficiency when signals having low percentage 30 modulation are received.

40 The control of the potential on the plate 148 of the control tube 140 through movement of the variable contacts 168 on resistor 172 also acts as a control of the current flow through the tube 140 and as a minimum bias control for the controlled amplifier tube. This control then controls the maximum sensitivity which may be reached by the amplifier.

When a strong signal is received the current flow through the detector 100 is high, causing 50 the drop across resistors 134 and 132 to be high, which increases the bias on that tube and reduces its sensitivity. At that same time, the potential of the control electrode 144 is made more positive and the current flow through the 55 tube 140 correspondingly high. The high current flow through the tube 140 causes a correspondingly large potential drop to cross the resistor in its place circuit, and thereby increases the bias on the amplifier tube by increasing the 60 potential between its cathode or ground and its grid, thus reducing its sensitivity.

In a similar manner, when the signal applied to the detector tube 100 is weak, the current flow through that tube is low, and the potential 65 drop across resistors 134 and 132 is correspondingly low. This decreases the potential between the cathode 108 and grid 104, and increases the gain or sensitivity of a detector. At the same time the potential of the control electrode 144 is 70 reduced to a less positive value and the current flow between the plate 148 and cathode 152 reduced. This decreases the potential between the plate 148 or grid 14 and ground, consequently increases the gain or sensitivity of the amplifier 75 fier 10.

At times it may be convenient to reduce the audio frequency output for a given set of detector operating conditions. This may be done by reducing the impedance 236 by short circuiting a part of it through the movable contact 238. 5

While the form of embodiment of the present invention as herein disclosed, constitutes a preferred form, it is to be understood that other forms might be adopted, all coming within the scope of the claims which follow. 10

What is claimed is as follows:

1. In a radio receiver having a high frequency amplifier, a detector and a circuit therefor, an audio frequency amplifier, a reproducer, and a source of direct and alternating current voltages, 15 the combination including, a control tube having a cathode, a control grid, an auxiliary grid, and a plate therein, a direct current connection between the plate and the high frequency amplifier input circuit, means coupling said control grid with the detector circuit, means including said source of direct current voltages for supplying a lower potential with respect to said cathode to the plate than to said auxiliary grid. 20

2. In a radio receiver having a high frequency amplifier, a detector having elements therein, and a reproducer, the combination including, a thermionic tube in said high frequency amplifier having a grid and cathode therein, an automatic gain control circuit, a thermionic control tube 30 having a control grid, an auxiliary grid, and a plate therein, means maintaining said control tube control grid at substantially the same potential as one of the elements of said detector, means maintaining the amplifier grid at substantially the same potential as the control tube plate, and means maintaining the amplifier cathode at a potential substantially that of the control tube auxiliary grid. 35

3. In a radio receiver having a high frequency 40 amplifier, a detector and a reproducer, the combination including, a thermionic tube in said high frequency amplifier having a grid and cathode therein, an automatic gain control circuit, a thermionic control tube in said circuit and 45 having a plate and auxiliary grid therein, and means maintaining said amplifier grid at substantially the same potential as the plate of said control tube, said plate potential being approximately equal to or lower than the potential of 50 said auxiliary grid whereby said gain control is accomplished with a relatively low potential on the control tube plate.

4. In a radio receiver having a detector, an amplifier, and an automatic gain control circuit, 55 the combination comprising, means including said automatic gain control circuit for controlling the gain of said amplifier, means including a portion of said automatic gain control circuit disposed in the detector space current path for 60 controlling the gain in said detector, means for predetermining the maximum gain in said detector, and said last means additionally being connected to the gain control circuit for predetermining the limit of the maximum gain attainable through the action of said automatic gain control circuit. 65

5. In a radio receiver having a detector including a grid, cathode and anode, an amplifier, and an automatic gain control circuit, the combination comprising, means including said automatic gain control circuit for controlling the gain of said amplifier, means comprising a variable resistor connected between the grid and cathode of the detector for predetermining the maximum 70 75 76

gain in said detector, and said last means being connected to said gain control circuit for pre-determining the limit of the maximum gain attainable through the action of said automatic 5 gain control circuit.

6. An automatic volume control circuit for a radio receiver having thermionic tubes therein, including in combination, a control tube having an anode, auxiliary grid, and control grid there- 10 in, said anode being connected with a grid of one of said thermionic tubes, means for adjusting the direct current potential on said anode, said auxiliary grid being at substantially the potential of the cathode of said one thermionic 15 tube, and said control grid being connected with another of said thermionic tubes.

7. An automatic volume control circuit for a radio receiver, including in combination, a thermionic control tube having a plate, an input ele- 20 ment, a cathode and an auxiliary element therein, means providing a lower direct current potential to said plate than to said other element, and means for varying the potential on said plate for controlling the maximum limit of sensitivity 25 of said receiver.

8. In an automatic volume control circuit for a radio receiver, a thermionic control tube having an anode and an auxiliary grid and operating with the plate at a lower potential than that

of said auxiliary grid, means for controlling the potential of one of said elements for adjusting one limit of the control action of said tube.

9. In an automatic volume control circuit for a radio receiver having a high frequency amplifier and a detector, the combination comprising, a thermionic control tube having a plate and auxiliary grid therein and operating with said plate at a lower potential than that of said auxiliary grid, and means including said tube for control- 10 ling the amplification of said amplifier.

10. In a radio receiver of the type including a signal amplifier whose gain is to be controlled, a tube for controlling the gain of said amplifier, said tube including a cathode, an input electrode, 15 an anode and an auxiliary cold electrode disposed adjacent said anode, means for impressing between the cathode and input electrode of said control tube signal-responsive energy whose amplitude variations control the variations in gain 20 of said amplifier, a direct current connection between the anode of said tube and an input electrode of said amplifier, and means for maintaining the anode of said control tube at a substantially less positive direct current potential 25 than said auxiliary electrode whereby said gain control action is secured with a low potential on the said anode of the control tube.

LAURENCE M. PERKINS.
